UNITED STATES PATENT OFFICE.

ALVIN L. COX, OF ELIZABETHTOWN, KENTUCKY.

WAGON-BED HOIST.

1,120,793.

Specification of Letters Patent. Patented Dec. 15, 1914.

Application filed October 31, 1913. Serial No. 798,525.

To all whom it may concern:

Be it known that I, ALVIN L. Cox, a citizen of the United States, residing at Elizabethtown, in the county of Hardin and State 5 of Kentucky, have invented certain new and useful Improvements in Wagon-Bed Hoists, of which the following is a specification.

My invention relates to hoisting means for wagon bodies, to remove the same from 10 the wheeled frame of the wagon, and has particular reference to means of the above mentioned character including a windlass or winding mechanism and means whereby such windlass or winding mechanism may 15 be detachably connected with the wagon body when the same is being elevated and disconnected therefrom after the wagon body has been raised to the desired position and suspended or otherwise supported in 20 such raised or elevated position.

An important object of this invention is to provide means of the above mentioned character, whereby a single windlass or winding means may be employed to elevate 25 any number of wagon bodies, when the same are provided with the necessary elements, to coöperate with the windlass or winding mechanism.

A further object of this invention is to 30 provide means of the above mentioned character, which are simple in construction, cheap to manufacture, strong and durable.

A further object of the invention is to provide means of the above mentioned 35 character which may be used in connection with different types of wagon bodies without materially altering their construction.

Other objects and advantages of the invention will be apparent during the course 40 of the following description.

In the accompanying drawings forming a part of this specification and in which like numerals are employed to designate like parts throughout the same, Figure 1 is a 45 side view of the hoisting means, showing the same applied to a wagon body, Fig. 2 is a plan view of the same, and, Fig. 3 is an end view of the same.

In the drawings, wherein is illustrated a 50 preferred embodiment of my invention, the numeral 4 designates a wagon body, of any well known or preferred type. This wagon body is preferably provided at its ends with transverse beams 5 and 6, rigidly attached thereto.

The numeral 7 designates a windlass as a

whole, comprising a rotatable shaft 8, provided at its outer end with a spool or drum 9, having ends or heads 10 and 11, as shown. At its inner end, the shaft 8 is provided with 60 an enlarged head 12'. The end beam 6 is provided with a U-shaped depending bracket or bearing 12, as shown.

Rigidly connected with the bottom of the wagon body 4 near and spaced from the end beam 6 is a transverse beam 13, which is thinner than the end beam 6, as shown. This transverse beam 13 carries a depending U-shaped bracket or bearing 14, rigidly attached thereto. Attention is called to the 70 fact that the bracket or bearing 14 is disposed in a horizontal plane above the bracket or bearing 12, as shown.

The brackets or bearings 12 and 14 are constructed sufficiently large to allow of the 75 passage therethrough of the shaft 8 and the head 12', carried thereby. When the shaft 8 is being inserted within the brackets or bearings 12 and 14, said shaft is slightly inclined, as shown by the dotted lines. The 80 shaft 8 assumes this position when being removed. When the windlass is being operated to elevate the wagon body, an upward pull being then exerted upon the outer end thereof, the rotatable shaft 8 assumes a suitable horizontal position, the outer portion of the same engaging the transverse end beam 6 and the inner portion thereof engaging the lower portion of the bracket or bearing 14. It is thus seen that 85 upon the longitudinal movement of the shaft 8 outwardly, the head 12' will engage the bracket or bearing 14, to prevent the improper displacement or removal of the windlass.

The head or end 11 is provided with an 90 extension 15, disposed within an opening 16 formed through the lower end of a locking lever 17, these parts being pivotally connected by a transverse bolt 18. The locking 95 lever 17 is provided at its free end with a head or catch 19, for a purpose to be described. The lever 17 is also provided at its outer end with a laterally extending handle or crank 19', as shown. The head 11 is also 100 provided with a radially inclined opening or notch 20, for a purpose to be described.

The numeral 21 designates suitably supported stationary or fixed supports or beams, carrying pulleys 22. These pulleys are 110 engaged by a flexible element 23, which may be a cable, chain, rope or the like. The

flexible element 23 has one end thereof provided with a loop 24, to be passed about the transverse beam 5 and the forward end of the wagon body 4. The opposite end of the flexible element 23 is provided with an enlargement or head 25, which may be formed by tying the rope in a knot or by other means. This end of the flexible element 23 is adapted to be inserted within the opening 10 20, the head 25 preventing the rope from accidentally moving out of the same. When the windlass 7 is rotated the flexible element 23 is wound upon the drum or spool 9, as is obvious.

15 Connected with the end of the flexible element 23 adjacent the windlass is a ring or link 26, adapted to receive a hook 27 attached to a loop 28, which is formed of a flexible element such as a rope, cable or 20 25 chain. The detachable loop 28 receives the rear end of the wagon and the end beam 6. The operation of the apparatus is as follows: The flexible element 23 preferably remains suspended from the pulleys 22. The 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 with the coöperating element 23 or the like. The lever 17 is adapted to be swung inwardly 50 during the rotation of the windlass 7, so that its head 19 will engage the flexible element 23, to lock the windlass against rotation. This is quite convenient in case the operator should desire to leave the wagon body before the same had been completely elevated.

It is to be understood that the form of my invention, herewith shown and described, is to be taken as a preferred example of the same, and that certain changes in the shape, size and arrangement of parts may be resorted to without departing from the spirit of the invention or the scope of the subjoined claim.

Having described my invention, I claim:—

A hoisting apparatus for wagon bodies, comprising a rotatable shaft adapted to be detachably connected with one end of the wagon body to extend longitudinally thereof, a spool formed upon the outer end of the rotatable shaft and provided with spaced heads, the outer head being provided with a slot extending inwardly from the outer edge thereof to detachably hold one end of a flexible element adapted to be wound upon the spool between the heads and to be connected with the wagon body, a radial extension formed upon the outer slotted head, an operating lever having an inner enlarged portion provided with an elongated opening to receive the radial extension, means pivotally connecting the inner enlarged portion of the operating lever with the radial extension, an inwardly extending catching finger adapted to engage with the flexible element and carried by the operating lever, and an outwardly extending handle carried by the outer end of the operating lever.

In testimony whereof I affix my signature in presence of two witnesses.

ALVIN L. COX.
